UNITED STATES PATENT OFFICE.

HIRAM F. McNUTT, OF RICHMOND, INDIANA.

AEROPLANE-DRIVE.

1,346,327.

Specification of Letters Patent.

Patented July 13, 1920.

Application filed December 20, 1918. Serial No. 267,581.

To all whom it may concern:

Be it known that I, HIRAM F. McNUTT, a citizen of the United States, residing in the city of Richmond, in the county of Wayne, State of Indiana, have invented new and useful Improvements in Aeroplane-Drives, of which the following is a full, clear, and comprehensive specification and exposition, the same being such as will 10 enable others to make and use the same with exactitude.

My invention relates to aeronautics, and particularly to the improvements in the means for driving aeroplanes or the like, 15 which means may be employed as the main drive, the auxiliary drive, the sole drive, or the associate drive, as desired.

The object of this invention, broadly stated, is to provide a driving mechanism 20 or propellers which will be strong and durable in construction, positive in action, easily operated and controlled, comparatively light in weight, and adapted to develop a maximum of propelling power with 25 a minimum of power transmitted from the power plant motor which may be connected therewith.

Other objects and particular advantages 30 will suggest themselves in the course of the following description, and that which is new and useful will be correlated in the appended claims.

The preferred means for carrying out 35 the principles of my invention in a practical manner is shown in the accompanying two sheets of drawings, in which—Figure 1 is a side elevation of my invention as applied to the body or fuselage of an aeroplane. Fig. 2 is a front elevation of the 40 construction shown in Fig. 1. Fig. 3 is a plan view of the main portions of my invention alone. Fig. 4 is a perspective view of one of the carriages and blades alone after being removed from the body of the 45 construction. Fig. 5 is an enlarged face elevation of one of the guide-blocks. Fig. 6 is a perspective view of one of the blades alone. Fig. 7 is a plan view of the crank-shaft of my propeller. And Fig. 8 is a de- 50 tail elevation of the gear shifting means.

Similar indices denote like parts throughout the several views.

In order that the construction, the operation, and the advantages of my invention 55 may be better understood and appreciated I will now take up a detailed description

thereof, in which I will set forth the various features as fully as I may.

In the drawings letter A designates the shell or the body of the fuselage. B denotes 60 the tail. C denotes the motor, which is located in the forward end portion of the fuselage. D denotes the main shaft which is driven by the motor. E denotes the ordinary propeller which is revolved by and 65 concentric with said shaft. F denotes the planes, including the frame-work connecting them, which extend out from and across the fuselage in the usual manner. Extending down from the forward portion of the 70 fuselage are the two spaced-apart hangers G and H, which carry the axle I, and on the end portions of the axle are mounted the ground wheels J and K.

All of said parts are of ordinary construction, and my invention is not to be limited thereto, as they are merely shown as examples.

The invention proper comprises the following: Numerals 1, 2, 3 and 4 denote the 80 members of a frame which is suspended below the fuselage and the planes by means of the hanger-arms 5, 6, 7 and 8. Numerals 9 and 10 denote the intermediate bars which connect the members 1 and 4, and extend parallel with the members 2 and 3 and 85 spaced therefrom, substantially as shown.

In this instance there are three sets of my propellers: one set located between the bars 9 and 10; one set between the bars 2 and 90 9 and 9; and one set between the bars 3 and 10. The only difference in the three sets of propellers being that the center set, between the bars 9 and 10, is at least double the width of the others.

Also each set of propellers is of double construction: a forward and a rear propeller construction, these are the same in every essential particular, except that the forward propeller of each set is driven direct by the 100 propeller crank-shaft, while the rear ones are driven by means which connect the forward and the rear propellers, as will hereinafter be explained.

One of my propeller mechanisms is 105 shown clearly in Fig. 4; and one of the propeller guide-blocks is shown enlarged in Fig. 5. And as the parts of each are duplicate of the others, therefore I will, for convenience of description, describe but one in 110 detail, and will designate the like parts in the others by the same indices.

Each of the propellers comprises the reciprocal cross-head, or head-block, 11 having notches *a* and *a'* in its ends in which the bars 2 and 9, for instance, are slidably fitted. Extending from the center of the forward face of the cross-head 11 are the ears *b* and *b'* in which the rear end of the pitman 12 is hinged. Extending upward and rearward from the head 11 are the hinge members *d* and *d'*. Numeral 13 denotes the blade-head, which is operative between the bars 2 and 9 but not in contact therewith. Extending upward and forward from the head 13 are the hinge-members *e* and *e'* which contact with the respective hinge-members *d* and *d'*, and to which they are normally connected by the hinge-rod 14, substantially as shown. Numeral 15 denotes the propeller-blade, having its upper edge rigidly secured to the rear face of the head 13. Secured on and extending back from the ends of the head 13 are the two arms 16 and 17, with their rear ends connected to the actuating head 18. Mounted on the ends of the head 18, and projecting in an axial direction therefrom, are the trunnions or rollers 19 and 20.

Each of the guide-blocks, shown in Fig. 5, includes an upper and a lower inturned horizontal flange 21 and 22, respectively, and angularly disposed end flanges 23 and 24, which merge into the respective short horizontal flanges 25 and 26, and these in turn merge into the flanges 22 and 21, thereby forming an irregular flange entirely around the edges of the guide-block. Said flanges extend from and are integral with the backing or base 27 of the guide-block. Numeral 28 denotes the frame or rocker, having its central portion pivotally mounted to the base 27 by means of the pivot 29. Said frame or rocker corresponds in general contour with the figure described by the flanges 21, 22, 23 and 24, but it is of less dimensions, whereby a channel is formed therearound, with a pocket channel 30 formed at one end between the flanges 21 and 26, and a similar pocket channel 31 at the other end, formed between the flanges 23 and 25. A spring 32 is attached at one end to the base 27, slightly forward of the pivot 29, with its other end attached to the frame 28, whereby the forward end of the frame is normally down, and the rear end normally up as shown in Fig. 5.

Two of the guide-blocks shown in Fig. 5 are provided for each of the carriage mechanisms shown in Fig. 4, they being arranged facing each other, one being carried by the member 2 and the other by the member 9. The roller 19 is adapted to operate in the channel of one guide-block, and the roller 20 being adapted to travel in the channel of the other guide-block, each of said rollers being adapted to travel around in its channel

of the respective guide-block. It will now be seen that if the carriage mechanism shown in Fig. 4, for instance, be moved forward to its limit then the rollers 19 and 20 will be located in their respective pocket channels 31, at which time the blade 15 will be in vertical position. Then as the carriage is moved rearward the rollers will travel back through the channel above the flange 22, then upward in contact with the flange 24, thereby swinging up the rear end of the frame 28, and permitting them to enter the pockets 30, which manifestly will turn the blades to almost horizontal position at the rear limit of the stroke of the pitman. Then as the pitman draws the carriage forward it is evident that the rollers 19 and 20 will be caused to travel in the channel between the upper edge of the frame 28 and the flange 21, which will carry the blade forward in practically horizontal position until the rollers force the forward ends of the frames, thereby permitting the rollers to pass down on the flange 23, and finally being located at the forward limit of the stroke, again locating the rollers in the pockets 31, which will bring the blade again to vertical position ready for a new stroke to the rear, and the operation will then be repeated as before. Located in the rear of the forward carriage above described is a rear carriage which is the same in every particular, except that the ears *b* and *b'* are dispensed with. The rear carriage is connected with its companion forward carriage by means of two rods, 33 and 34, which are secured to the heads 11 of the two carriages, whereby they will slide forward and backward in unison.

Numeral 35 denotes the crank shaft of the propeller, it having three U-shaped cranks, one for each of the three pitmen 12, whose forward ends are revolubly connected thereto.

The said shaft 35 is mounted in suitable bearings carried by the lower portion of the frame of the fuselage, or other suitable part of the device. Secured on the shaft 35 is the gear wheel 36, which is adapted to mesh with the floatable pinion 37, which may be geared to slide forward and backward. The pinion 37 is adapted to mesh with the gear 38. The gear 38 is formed integral with larger spiral gear wheel 39, which latter meshes at right angles with the spiral pinion 40, the latter being secured on the main shaft D.

The means for placing the crank-shaft 35 in and out of gear with the main shaft D, consists in having the pinion 37 formed floating that is adapted to move forward and backward into and out of mesh with the gears 36 and 38 in any well known manner.

It is evident, from the shape of the crank-

shaft 35, that when the two outside pairs of blades are moving rearward that the center pair of blades will be moving forward, and vice-versa. And also that as the blades move rearward they will have a maximum of air resistance, thereby forcing the machine forward, and that when they are moving forward they will have a minimum of air resistance.

10 In Fig. 1 is shown a clutch by which the propeller E may be engaged with or detached from the shaft D. The hub 41 of the propeller is revolubly mounted on the shaft D, and it has notches 42 in its rear end which when the hub 41 is slid rearward will engage the pin 43 which extends through the shaft D, whereby the propeller E will be revolved with the shaft D. A channel 44 extends around in the periphery of the hub 41 in which is located the hook end of the arm 45 which extends back into the fuselage, to be in reach of the operator.

15 The shafts of the gears 36 and 38 are mounted in a frame 48, shown in Fig. 8, which is carried by the lower portion of the fuselage. Extending forward from the frame 48 are the horizontal arms 47 in which are slidably mounted the bearings 48 which carry the shaft of the pinion 37. A lever 49 extends back from the bearings 48 to be in reach of the operator, whereby the pinion 37 may be slid forward and backward out of and into gear with the gears 36 and 38.

20 In practice my propeller may be operated with and in addition to the regular rotary propeller E, or the propeller E may be cut out and my propeller alone may be employed, or my propeller may be cut out and the propeller E alone may be employed, all 25 at the will of the operator located in the fuselage.

25 It is also evident that the principles of my invention may be employed with a hydroplane, or with boats, or other crafts, as well 30 as with various types of air crafts.

35 I desire that it be understood that various changes may be made in the various details of construction, from that herein shown and described, without departing from the spirit 40 of my invention and without sacrificing any of the advantages thereof.

45 Having now fully shown and described my invention, what I claim and desire to secure by Letters Patent of the United States is,—

50 1. In combination with a fuselage having a motor carried thereby and a revolving propeller operated by the motor, sets of propellers slidably mounted under said body, each set moving in a direction opposite to 55 the set next thereto, all of said sliding propellers being adapted to push the body forward when they are moving in one direction and to operate idle when moving in the op-

posite direction, all of said sliding propellers being adapted to be placed in and out of gear with said motor, and means for placing the revolving propeller into and out of gear with the motor, all substantially as shown and described.

2. In combination with a fuselage having a motor carried thereby and a rotary propeller adapted to be operated by the motor, a series of reciprocating propellers located under said body and adapted to alternate backward and forward with relation to each other, means for causing the blade of the reciprocating propellers to have a maximum of air resistance when moving in one direction and a minimum air resistance when moving in the opposite direction, and means for operating said blades by the power of the motor.

3. An aeroplane drive having, in combination with a fuselage, series of propellers suspended below the fuselage, carriages arranged parallel and side by side with relation to each other, blades for each carriage arranged tandem, means for driving the carriages alternative forward and backward, guides for controlling the positions of the blades whereby they will stand horizontal when moving forward and vertical when moving rearward, an eccentric crank-shaft for driving the carriages, a motor for driving the crank-shaft, and means for disengaging the crank shaft from the motor.

4. In combination with a fuselage having a motor and a rotary propeller carried thereby, a trio of reciprocating carriages suspended abreast of each other under the fuselage and adapted to be operated by the motor, each carriage including a rear and a forward blade, and a center carriage having its blades of double the length of the blades of the outer carriage, means for gearing the outer carriages to operate in the same direction at the same time and alternating with the movements of the center carriage, a pivot at the upper corners of each blade, a roller on each pivot, a pair of guide-blocks for each blade, the same having channels therein for their respective rollers, a switch for each guide block, means for reciprocating said carriages whereby the pivots of the blades travel in their channels planetarily to cause the blades to move rearward against the air and forward in edgewise position to cut the air, all substantially as shown and described.

5. In testimony whereof I have hereunto subscribed my name in the presence of two subscribing witnesses.

HIRAM F. McNUTT.
